(57) CLAIM

The ornamental design for a bag as shown and described.

DESCRIPTION

FIG. 1 is a front view of a first embodiment of a bag showing our new design;

FIG. 2 is a back view thereof;

FIG. 3 is right side view thereof;

FIG. 4 is a left side view thereof;

FIG. 5 is a top view thereof;

FIG. 6 is a bottom view thereof;

FIG. 7 is a front view of a second embodiment thereof;

FIG. 8 is a back view of FIG. 7;

FIG. 9 is a right side view of FIG. 7;

FIG. 10 is a left side view of FIG. 7;

FIG. 11 is a top view of FIG. 7; and,

FIG. 12 is a bottom view of FIG. 7.

Broken lines in FIGS. 1-12 form no part of the claimed design. The dot-dash boundary lines in FIGS. 1, 3, 4, 7, 9 and 10 represent the bounds of the claim and form no part of the claimed design. The dash-dash lines visible on the surface of the bag above the claimed line detail represents stitching and forms no part of the claimed design.
